UNITED STATES PATENT OFFICE.

CHARLES E. PHILLIPS, OF ABINGTON, MASSACHUSETTS.

IMPROVEMENT IN HEADING-TOOLS FOR SCREWS.

Specification forming part of Letters Patent No. 37,703, dated February 17, 1863.

To all whom it may concern:

Be it known that I, CHARLES E. PHILLIPS, of Abington, in the county of Plymouth and State of Massachusetts, have invented a new and Improved Heading-Tool for Screws, &c.; and I do hereby declare that the following is a full, clear, and exact description of the same, reference being had to the accompanying drawings, forming a part of this specification, in which—

Figure 1 represents a longitudinal vertical section of my invention. Fig. 2 is a front elevation of the same. Fig. 3 is a side elevation of a screw-blank headed by my tool.

Similar letters of reference in the three views indicate corresponding parts.

The invention consists in the employment, for the purpose of slotting and forming the heads of screw-blanks, of a tool made of two jaws, provided in one end with a cavity to fit to the desired heads, and held together by a suitable screw-clamp, in combination with an adjustable slotting tongue or blade, in such a manner that the same tool which forms the head forms at the same time the slot in one below, and that the slotting blade can be adjusted to suit screw-heads of different sizes and slots of different depths, and that by removing the slotting-tongue the cavity of the heading-tool can be polished, so that the same produces well finished heads.

To enable those skilled in the art to make and use my invention, I will proceed to describe its construction and operation with reference to the drawings.

My heading-tool A consists of two jaws, B C, which are secured together by means of a screw-clamp, D'. The jaw B is provided with a shoulder, a, the upper surface of which is flush with the upper surface of the jaw C, when the two jaws are put together, and steady-pins b, inserted into the inner surface of the jaw C, and fitting into suitable sockets on the jaw B, serve to retain the two jaws in the proper relation to each other. Between the two jaws B C a recess, c, is formed to receive and guide the slotting-blade D. To the inner end of this blade a round pin, d, is secured, which fits into a corresponding socket,

e, formed between the two jaws, and a screw, f, which passes through the shoulder a of the jaw B, serves to adjust the blade D. Said screw acts on the end of the pin d, and by turning it in the proper direction the blade D is pushed out flush with the end of the tool. This end is provided with a cavity, g, corresponding in size to the heads of the screw-blanks to be produced. In order to produce well-finished heads, it is indispensable that this cavity shall be polished. If the slotting-blade is rigid with the jaws, the operation of polishing cannot be accomplished, whereas with my tool the blade can be removed and replaced by a piece of sheet metal, the end of which corresponds in shape to the inner surface of the cavity g, and in this state the cavity can be polished the same as if it were cut into a solid piece of steel. After the polishing operation is accomplished the slotting-blade is replaced between the jaws, and the tool is ready for use.

My tool is secured in a lever or fastened to any other suitable part of a screw-blank machine, which is pressed against the head of the screw-blank while the body of the screw-blank is secured between the dies through which it is formed. Simultaneously, when the head is formed, the blade D, by coming in contact with the face of the head, makes an impression or slot in it, as clearly shown in Fig. 3 of the drawings. If the end of the blade wears off, it can be easily sharpened and adjusted to the desired position by the screw f, and by means of this screw the depth of the impression or slot in the head of the blank can be regulated.

Having thus fully described my invention, what I claim as new, and desire to secure by Letters Patent, is—

The arrangement of the adjustable and removable blade D, in combination with the jaws B C, constructed and operating substantially as herein described, for the purpose specified.

CHARLES E. PHILLIPS.
